UNITED STATES PATENT OFFICE.

OLIVER J. JOHNSON, OF WHEELING, WEST VIRGINIA.

FEED MECHANISM FOR METAL SHEETS.

No. 810,152.

Specification of Letters Patent.

Patented Jan. 16, 1906.

Application filed January 27, 1904. Serial No. 190,815.

To all whom it may concern:

Be it known that I, OLIVER J. JOHNSON, a citizen of the United States, residing at Wheeling, in the county of Ohio and State of 5 West Virginia, have invented new and useful Improvements in Feed Mechanism for Metal and Analogous Sheets, of which the following is a specification.

This invention relates to a machine or 10 mechanism for feeding metal or analogous sheets, one by one, from a pile or stack, and more particularly to a feed mechanism or machine for successively feeding can-body blanks to the reciprocating carrier or conveyer of a can-body-making machine of the 15 type described in my application for United States Letters Patent, Serial No. 133,031, filed November 28, 1902.

The feed machine or mechanism comprises 20 a holder in which a pile or stack of blanks are placed on edge and an oscillating pneumatic feed device which carries the blanks successively from the pile to an inclined chute by which they are delivered to the reciprocating 25 conveyer.

The object of the invention is to provide a feed mechanism or machine of simple and practical construction which will deliver the blanks in rapid succession to the body-making 30 machine or other machine for operating upon blanks and will preclude the feeding of more than one blank at a time.

In the accompanying drawings, consisting 35 of four sheets, Figure 1 is a vertical longitudinal section, partly in elevation, of a feed mechanism embodying the invention and a portion of a can-body-making machine to which the same is applied. Fig. 2 is a plan view thereof, partly in horizontal section. Fig. 3 is a fragmentary vertical sectional elevation showing the blank restraining and impelling devices. Fig. 4 is a fragmentary front elevation of the feed mechanism viewed 40 in the direction of the arrow X, Fig. 1. Fig. 5 is a plan view, partly in section, thereof, viewed in the direction of the arrow Y, Fig. 1. Fig. 6 is a front elevation, partly in section, in line 6 6, Fig. 1. Fig. 7 is a fragmentary sectional elevation of a slightly-different restraining device. Fig. 8 is a side elevation, 45 on a reduced scale, showing a blank-feed machine complete in itself independently of the body-making machine and provided with a valve mechanism for establishing and destroying the vacuum in the vacuum feed device.

Like letters of reference refer to like parts in the several figures.

Referring particularly to Figs. 1 to 6, A represents a standard or upright portion of 60 the main frame of a can-body-making machine, and a a rearwardly-projecting horizontal bracket or frame extension which supports the blank-feed table B and reciprocating 65 carrier or conveyer C, which successively carries the blanks delivered thereto by the feed mechanism to the edging mechanism, which forms the side-seam hooks on the opposite edges of the blanks or other mechanism for operating upon the blanks. The blank-conveyer is reciprocated horizontally by a rock-shaft D, which is connected to the conveyer by a rock-arm d and link d' and is rocked by any suitable mechanism. (Not 70 shown.) The parts thus briefly described 75 are fully shown and described in my application for patent above identified.

E represents two upright parallel standards bolted or otherwise secured on the horizontal frame-bracket and constituting a supporting-frame for the feed mechanism. 80

The blanks X are placed in a pile or stack on edge in an inclined position in a holder or supply-box F of suitable form mounted on the feed-frame. The blank-holder shown in 85 the drawings is constructed as follows: f f represent oppositely-disposed parallel holder bars or plates, which are arranged in an inclined position between the feed-frame standards and support the pile of blanks. They 90 have vertical side portions f', between which the blanks are held from lateral displacement. The supporting-bars are provided at their front ends with perforated lugs, through which loosely passes a horizontal rod g, secured at its opposite ends to the feed-frame standards, and are capable of sliding and swinging on the supporting-rod to adjust them laterally and as to vertical inclination. 95 They are secured when adjusted by set-screws 100 or the like g'. The rear ends of the blank-holder bars are adjustably supported by angle-brackets g'', having vertical slotted arms secured to the feed-frame standards by bolts g''' and horizontal slotted arms on which the 105 blank-holder bars are secured by bolts g''. The holder-bars are thus adjustable laterally to accommodate and properly center blanks of different widths and vertically to give them the necessary inclination to insure the 110 proper sliding of the pile of blanks forwardly in the holder. The blanks are held from es-

caping from the front end of the blank-holder by retaining lips or flanges formed by strips *h*, Fig. 4, secured to the front ends of the holder-bars and extending inwardly therefrom.

The blanks are taken successively from the front of the pile in the blank-holder and delivered to the reciprocating conveyer by a feed device *I*, preferably in the form of a low vacuum-cup provided with an operative rear face of suitable yielding material, such as rubber, which insures a reliable hold on the blanks. The vacuum-cup is connected by a flexible hose *i* and suitable connections (not shown) with means (also not shown) for establishing a vacuum therein, so that the blank is held thereon by atmospheric pressure when the cup is pressed against the face of the blank. The air can be exhausted from the cup and connections directly by a vacuum-pump or, preferably, by an apparatus including a main vacuum-tank, a pump for exhausting the same, and an auxiliary vacuum-chamber in the connection between the main vacuum-tank and each feed mechanism where a plurality are employed. The feed device is secured to the lower end of a swinging feed-arm *K*, which is secured at its upper end to a horizontal rock-shaft *k*, journaled in suitable bearings in the upper front ends of the feed-frame standards and provided at one end with a rock-arm *k'*, connected by a link *k²* with a rock-arm *k³* on the operating rock-shaft *D* for the blank-conveyer. The link is preferably connected with the rock-arm *k³* by a pin or bolt adjustable toward and from the operating rock-shaft in an elongated slot *k⁴* in the rock-arm to enable the length of throw of the feed-arm to be regulated as necessary.

L represents a blank chute or guide and stripping device arranged in front of the blank-holder and preferably consisting of side and intermediate rails inclining downwardly and rearwardly toward the reciprocating conveyer. The chute-rails are secured at their upper ends to a substantially U-shaped yoke or frame *l*, the side arms of which extend between guide-ribs on the feed-frame standards, to which they are adjustably secured by bolts *l'*, passing through slots in the arms of the yoke. The side chute-rails are preferably provided with vertical flanges between which the blank is confined and held from lateral movement while sliding down the chute, and all of the rails are preferably curved at their lower ends to turn the blanks more nearly into a horizontal position and prevent a too sudden and violent impact of the same against the blank-conveyer.

The operation of the feed mechanism is as follows: Upon each forward movement of the reciprocating conveyer *C* to carry a blank into the body-making machine the feed-arm *K* is swung by the described operating mech-

anism toward the pile of blanks and presses the vacuum-cup *I* firmly against the foremost blank of the pile, and as the air is exhausted from the vacuum-cup by the vacuum apparatus the blank is caused to adhere thereto by atmospheric pressure. As the blank-conveyer makes its return or rearward movement the feed device pulls or snaps the foremost blank out of the holder from between the retaining-lips and carries it forward against the guide and stripping chute *L*. The lower edge of the blank strikes the chute first and is thereby pressed or tilted forwardly away from the lower edge of the vacuum-cup, so that air is admitted to the latter and the blank released and permitted to slide down the chute onto the reciprocating conveyer in front of the rear pair of feed-dogs thereof and in position to be carried forward by the latter.

To prevent the sheet from buckling when it strikes the blank-chute, and thereby defeating the proper stripping of the same from the feed device, the two intermediate chute-rails are connected just below the feed device by a transverse bar or strip *l²*.

Difficulty has been experienced in feed mechanisms of the character described to prevent the feed device from pulling more than one blank at a time from the blank-holder, as two or more blanks sometimes cling together, owing to the bur on the edges of the blanks and the friction between the blanks caused by the weight of the pile on the foremost blanks. This is overcome in the present machine by restraining fingers or devices *M*, which are secured to some suitable part of the machine, such as the yoke *l*, and bear on the edge of the foremost blank of the pile. Two fingers are shown, which are of spring metal and have hooked ends which engage the top edges of the blanks with sufficient force to prevent the movement of the second or subsequent blanks with the first blank which is firmly held by the vacuum-cup and insure the feeding of but one blank at a time. One or more such restraining-fingers *M* could be employed, as desired, and they could engage the bottom or other edges of the blanks instead of the top edges, as shown.

Instead of the spring-fingers one or more rigid restraining fingers or devices *O*, such as shown in Fig. 7, bearing against the edges of the blanks would accomplish a similar result. In the latter case the arrangement of the restraining device should be such that the first blank held by the feeding device would have to spring somewhat to pass the restraining device, and as the second or subsequent blanks would not be firmly held to the first blank it or they would be held back.

P represents spring devices secured to the yoke *l* or other suitable part of the machine for impelling or throwing the blanks quickly

down on the reciprocating conveyer when released by the feed device while the conveyer is at rest at the end of the backward stroke. If a blank is bent or for any other reason 5 clings in the chute, it might not reach the conveyer before the forward movement of the same. The impelling device could be omitted and the blank be allowed to drop on the conveyer and ride over the dogs in their rearward movement; but this is not desirable, as it necessitates the use of low feed-dogs, which in case the blank is buckled would pass under the blank in their forward movement and would not catch and carry it forward. A 10 device or devices of any other construction and arrangement could be used in place of those described; but they are efficient and reliable.

In the mechanism above described a valve 20 for destroying the vacuum is not necessary to the practical operation of the feed device, for the movement of the same is so short and it is out of contact with the blank for such a short period of time that the vacuum is not 25 impaired to an extent to effect the economical operation of the machine. If preferred, however, a valve can be employed for the feed device, and in Fig. 8 a feed-machine is shown involving a valve. This figure also shows a 30 feed-machine complete in itself independently of the machine for operating upon the blanks and capable of use in connection with any sort of machine. In this modified form the feed device Q is constructed and operates 35 as before described, but is mounted on a separate independent frame q and is actuated from a rotary drive-shaft R by a crank-wheel r, link r', and rock-arm r'', secured to the rock-shaft for the feed device. The pipe or connection 40 between the feed device and vacuum apparatus is provided with a valve S, of any suitable form, which in one position does not obstruct the pipe-passage and in another position opens the pipe to the atmosphere. The 45 valve is actuated by a cam T on the drive-shaft and a lever t, which is oscillated by the cam and engages the valve-stem. Any suitable valve and operating means for the same and the feed device can be employed.

50 While a pneumatic feed device such as described is deemed preferable, the other described features of the feed mechanism would also be desirable with a feed device of different character—such, for instance, as an electromagnetic feeder—and the claims for such 55 other features are not restricted to a construction employing a pneumatic feed device.

The feed devices described pull the blank 60 directly from the blank-holder in a direction substantially at right angles to the plane of the blanks in the holder, and the blank is maintained in substantial parallelism with this position until it is detached from the feed device. While the swinging feed device arranged 65 as described is deemed preferable for

accomplishing this result, manifestly feed devices mounted and operating in different ways could be employed to produce a like end.

I claim as my invention—

1. The combination of a holder in which 70 the blanks stand on edge, a stationary chute arranged in front of said holder and inclining downwardly toward the latter, a feed-arm arranged between said blank-holder and said chute and hung from above to swing back and 75 forth between the holder and the chute, a feed device on said arm which is pressed against the faces of the blanks and to which the blanks adhere, and means for oscillating said feed-arm, whereby the blanks are 80 removed from said holder and delivered to said chute with their front faces down, substantially as set forth.

2. The combination of an inclined holder 85 in which the blanks stand on edge in an inclined position, a chute arranged in front of said holder and inclining in substantially the same direction as the blanks in the holder, a pivoted feed-arm arranged between said blank-holder and said chute, a feed device on 90 said arm for holding the blanks, and means for oscillating said feed-arm, whereby the blanks are removed from said holder and delivered to said chute with their front faces 95 down, said chute serving to strip the blanks from said feed device, substantially as set forth.

3. The combination of a holder for supporting a pile of blanks on edge, retaining lips which engage the sides of the foremost 100 blank to retain the blanks in the holder, an oscillating feed device for removing the blanks separately from said holder, and a stationary restraining device past which the blank secured to the feed device is carried by the latter and which bears against the edges only of the blanks to prevent the removal of more than one blank at a time from the holder, substantially as set forth.

4. The combination of a holder for supporting a pile of blanks on edge, a feed device 110 for removing the blanks separately from said holder, and a stationary restraining device past which the blank secured to the feed device is carried and which scrapes across the 115 edge of the blank carried by the feed device to hold back succeeding blanks and prevent the removal of more than one blank at a time from the holder, substantially as set forth.

5. The combination of a holder for supporting a pile of blanks on edge, a feed device 120 for removing the blanks separately from said holder, and a stationary restraining device past which the blank secured to the feed device is carried by the latter and which bears 125 against the edges only of succeeding blanks to prevent the removal of more than one blank at a time from the holder, substantially as set forth.

6. The combination of a holder for sup- 130

- porting a pile of blanks on edge, a feed device for removing the blanks separately from said holder, and a yielding restraining-finger past which the blank secured to the feed device is carried by the latter and which bears against the edges only of succeeding blanks to prevent the removal of more than one blank at a time from the holder, substantially as set forth.
10. The combination of a holder for supporting a pile of blanks on edge, an oscillating feed device for removing the blanks separately from said holder, and a yielding restraining-finger past which the blank secured to the feed device is carried by the latter and which bears against the top edges only of succeeding blanks to prevent the removal of more than one blank at a time from the holder, substantially as set forth.
15. The combination of a holder for supporting a pile of blanks on edge, retaining-lips which engage the sides of the foremost blank to retain the blanks in the holder, an oscillating feed device for removing the blanks separately from said holder, and a yielding restraining device past which the blank secured to the feed device is carried by the latter and which bears against the top edges of the succeeding blanks to prevent the removal of more than one blank at a time from the holder, substantially as set forth.
20. The combination of a holder for supporting a pile of blanks on edge, retaining-lips which engage the sides of the foremost blank to retain the blanks in the holder, an oscillating feed device for removing the blanks separately from said holder, and a yielding restraining device past which the blank secured to the feed device is carried by the latter and which bears against the top edges of the succeeding blanks to prevent the removal of more than one blank at a time from the holder, substantially as set forth.
25. The combination of a holder for supporting a pile of blanks on edge, retaining-lips which engage the sides of the foremost blank to retain the blanks in the holder, an oscillating feed device for removing the blanks separately from said holder, and a yielding restraining device past which the blank secured to the feed device is carried by the latter and which bears against the top edges of the succeeding blanks to prevent the removal of more than one blank at a time from the holder, substantially as set forth.
30. The combination of a holder for sup-

porting a pile of blanks on edge, an oscillating feed device for removing the blanks from said holder, an inclined chute to which the blanks are carried by said feed device, and a spring propelling device arranged above the path of the blanks, and which is engaged and deflected by the blank carried by the feed device and which throws the blank quickly down the chute when released from said feed device, substantially as set forth.

35. The combination of a frame, a horizontal supporting-rod, a blank-holder comprising bars mounted for vertical swinging and lateral adjustment on said supporting-rod, and brackets vertically adjustable on said frame, and on which said blank-holder bars are laterally adjustable, substantially as set forth.

40. The combination of a frame, a blank-holder supported thereby, a yoke having arms adjustably secured to said frame, a blank-chute secured to said adjustable yoke in front of said blank-holder, and a feed device arranged between said blank-holder and chute for carrying the blanks from the former to the latter, substantially as set forth.

45. Witness my hand this 20th day of January, 1904.

OLIVER J. JOHNSON.
